CLAIM

The ornamental design for a clothing hanger, as shown and described.

DESCRIPTION

FIG. 1 is a top plan view of a clothing hanger showing my new design;

FIG. 2 is a left side elevational view thereof;

FIG. 3 is a front elevational view thereof, the rear elevational view being a mirror image thereto;

FIG. 4 is a right side elevational view thereof;

FIG. 5 is a bottom plan view thereof; and,

FIG. 6 is an enlarged perspective view thereof.
